UNITED STATES PATENT OFFICE.

EDWARD C. TOBIN, OF STOCKTON, CALIFORNIA

KNIFE-SHARPENER.

1,215,591.

Specification of Letters Patent. Patented Feb. 13, 1917.

Application filed March 8, 1916. Serial No. 82,988.

To all whom it may concern:

Be it known that I, EDWARD C. TOBIN, a citizen of the United States, residing at Stockton, in the county of San Joaquin and State of California, have invented certain new and useful Improvements in Knife-Sharpener, of which the following is a specification, reference being had to the accompanying drawings.

10 This invention relates to sharpening devices, and particularly to devices for sharpening knives, scissors, and like blades.

15 The general object of this invention is the provision of a very simple, cheaply made, easily operated and effective device of this character, and further to provide co-acting sharpening disks normally held from relative rotation but shiftable so that new sharpening surfaces may be presented whenever desired.

20 Still another object of the invention is the provision of means which will adapt the device to sharpening scissors, this means being shiftable into a position where it will prevent one face of a blade from coming in contact with the sharpening disk.

25 Still another object of the invention is the provision of a base which not only supports two sets of co-acting sharpening disks, but also supports a whet stone or hone in convenient position for use.

30 Other objects will appear in the course of the following description.

35 My invention is illustrated in the accompanying drawing wherein;

Figure 1 is an end elevation of my improved sharpener;

Fig. 2 is a longitudinal section on the line 2—2 of Fig. 1;

40 Fig. 3 is a top plan view of the device; and

Fig. 4 is an elevation partly in section of one of the pair of sharpening disks.

45 Fig. 5 is an elevation looking toward the inside face of the sharpening device;

Fig. 6 is a fragmentary vertical section through the disk 26, the plates 16 and 19, the hub 18, and the guard 33.

50 Referring to these figures, 10 designates a base which is approximately rectangular in form as illustrated clearly in Fig. 3, and provided with the feet 11, whereby the base may be attached to a support. The end wall 12 of this base is extended upward 55 above the base and is formed at its middle

with a downward extended V-shaped notch 13 which divides the upper portion of this end wall into two lobes 15 and 16. Securely attached to the lobe 15 and extending out therefrom is a hub 17, and securely attached to the lobe 16 is a hub 18 which is counter-bored and screw-threaded. Disposed in parallel relation to the end plate 12 is a supporting plate 19 which has approximately the same form as the plate 12, and which is divided by a vertically-disposed notch into lobes 20 and 21. The lower end of the plate 19 is formed with inwardly extending feet 22 and passing through the plate 19 is a screw 23 which engages with a screw-threaded opening 24 formed in the plate 12.

55 The hubs 17 and 18 form arbors for the support each of a pair of sharpening disks designated 25 and 26. Each pair of sharpening disks is integrally connected by a hub portion 27 which is borel to surround the corresponding hub 17 or 18 and the margin of each disk is beveled or sharpened at 28. Disposed between the pair of sharpening 60 disks 25 and the plate 12 is a washer 29 while disposed between the pair of sharpening disks 26 and the plate 19 is a washer 30. The sharpening disks of one pair are thus disposed in staggered relation to the 65 sharpening disks of the other pair as illustrated most clearly in Fig. 3. These pairs of sharpening disks are rotatable upon their hubs 17 and 18 but may be held from any rotation by turning upon the screw 23 70 causing the plate 19 to frictionally engage the sharpening disks and prevent any movement of the sharpening disks.

75 Extending into the counter-bore of a hub 18 is a screw 31, and pivotally mounted upon this screw 31 is a L-shaped guard 33 which extends radially outward then is bent transversely over the edges of the disks 26 and then extends radially inward for a short distance against the face of the plate 100 12. When this guard 33 is turned to the position shown in full lines in Fig. 1, it is ineffective, but when it is turned to dotted line position in this figure, it provides for 105 the sharpening of scissors or like blades.

100 Disposed within the rectangular base 10 and supported therein in any suitable manner, is a whet stone 34.

105 In practical use when it is desired to sharpen a knife or like blade, the guard 33 110

is turned back to the full line position in Fig. 1, and the knife placed lightly down between the oppositely disposed sharpening disks 25 and 26, so that the knife extends 5 parallel to the axes of these disks, the edge of the knife being of course downward. The knife is then drawn lightly along the edges of the disks until a sufficient edge has been secured. If the sharpening edges of 10 the disks become dull and ineffective, the screw 23 is loosened permitting the disks 25 and 26 to be turned so as to present a new edge or surface in the cleft formed between the disks. When so adjusted, the disks are 15 again clamped against rotation. If it be desired to sharpen scissors or like implements having one face of the blade flat and the other face with a beveled edge, the guard 33 is turned to the dotted line position in 20 Fig. 1, and this holds the blade from contact with the disks 26, and the other disks 25 operate upon the blade. The use of the hone or whet stone 34 will be obvious. It is plain that the disks 25 and 26 may be readily 25 removed for regrinding when desired, and that new disks can be readily inserted. The device is very simple and can be cheaply made, and is small enough to permit it to be placed in a convenient position on the 30 desk without interfering with the ordinary use of the desk.

Having thus described my invention what I claim is:

1. A sharpening device including supporting members oppositely disposed sharpening disks rotatably mounted upon said supporting members and having slightly overlapping margins, means for holding said sharpening disks from rotation, and a guard 35 shiftable into a position over one of said 40 sharpening disks and in proximity to the intersection of the disks.

2. A sharpening device including supporting members oppositely disposed sharpening disks rotatably mounted upon said 45 supporting members and having slightly overlapping margins, means for holding said sharpening disks from rotation, and a guard shiftable into positions over one of said 50 sharpening disks and in proximity to the 55 intersection of the disks, said guard being pivotally mounted upon one of said supporting members, extending radially outward and transversely across the sharpening disks.

In testimony whereof I hereunto affix my signature in the presence of two witnesses.

EDWARD C. TOBIN.
